TRANSDUCER ELEMENT MOUNTING

John D. Wallace, Oreland, Pa.

Application September 19, 1952, Serial No. 310,571

5 Claims. (Cl. 340—11)

(Granted under Title 35, U. S. Code (1952), sec. 266)

The invention herein described may be manufactured and used by or for the Government of the United States of America for governmental purposes without the payment of any royalties thereon or therefor.

The present invention relates to magnetostrictive transducers and more particularly to devices for mounting and assembling transducer elements.

Mounting and assembly of piston-type transducer elements have previously been accomplished by gluing a plastic end cap on the edges of such elements. Alignment was attained by having a projection on the end caps fit into recesses in a mounting ring. This end-cap method of alignment placed the plastic load along the edge of the elements and in such a position so as to clamp the vibration of the element. In order to replace an element using the aforementioned mounting, the mounting ring must first be removed. Removal of this ring disturbed all the elements thereby requiring realignment of the elements. The electrical connectors to the elements were threaded through the end caps and mounting ring. Said connectors required breaking for all the elements to allow removal of the mounting ring.

In order to overcome the disadvantages enumerated above, it is an object of the present invention to provide a mounting wherein the above-described defects are eliminated.

Another object is to provide a device for mounting transducer elements securely and easily, wherein single elements can be removed without disturbing the remaining ones.

Still another object is to provide a mounting device for transducer elements wherein alignment is automatic.

These and other objects of the invention and the various features and details of construction and operation thereof are hereinafter more fully set forth and described with reference to the accompanying drawing in which like numbers refer to like parts.

Scanning sonar transducers require a large number of magnetostrictive elements for proper operation. Space requirements and means for supporting the many elements present a severe problem. Since the spacing of the elements should be approximately a half-wave length, said elements must be packed close to each other leaving little space for supporting the elements by placing heavy structures between them. Then, too, the inside ends of the elements must be free to vibrate necessitating a support to be applied at the nodal plane of the elements.

One method of constructing and mounting transducer elements is illustrated in this invention. The drawing is a partial-pictorial view of a portion of the invention showing two magnetostrictive elements 1 bearing against pressure-releasing backing 3. Windings 5 are placed on the magnetostrictive elements as indicated in the drawing. Said elements are constructed in the form of a laminated stack having "hips" 7 located at the nodal plane of the elements. Said pressure-releasing material located between the base of the stack and a supporting shell or base 9 must act as an efficient pressure release to the

2

mechanical vibrations set up at the bottom end of the stack.

Holding members 11 made of plastic or other suitable material can be accurately molded or machined to conform with hips 7 of magnetostrictive elements 1. Said holding members serve to hold elements 1 against pressure releasing material 3. Alignment blocks 13 are notched at the top to conform with holders 11 and are fixedly mounted at the bottom in grooves in supporting base 9. The height of said alignment blocks is such as to allow members 11 to hold elements 1 securely against pressure-release material 3. Caps 15 are mounted over the ends of holders 11 when in recesses 19 in alignment blocks 13 thereby retaining said holders in the recesses and against hips 7 of elements 1. Retaining screws 17 in caps 15 prevent said caps from becoming disengaged from blocks 13. Alignment of magnetostrictive elements 1 is accomplished by properly machining slots 19 in alignment blocks 13 so that holders 11 are slidably in said slots and mate with hips 7 on the elements 1.

A magnetostrictive element 1 can be replaced by removing two aligned caps 15 on each side of said element. Removal of said caps permits holders 11 to be slid out of recesses 19 thereby freeing the element 1 from restraint without disturbing the remaining elements. A new element 1 can then be substituted for the removed one and aligned with no difficulty since holders 11 mate with elements 1 and recesses 19 in blocks 13.

From the foregoing description and illustration it is apparent that the present invention provides means for assembling a transducer in a jig and then placing said transducer in a housing of suitable design. Single magnetostrictive elements can be easily removed or replaced without disturbing the remaining elements and alignment of said elements is automatic.

While a particular embodiment of the invention has been shown and described herein, it is not intended that the invention be limited to such disclosure, but that changes and modifications can be made and incorporated within the scope of the claims.

What is claimed:

1. A mounting for maintaining transducer elements in alignment comprising a base for supporting magnetostrictive elements, alignment blocks supported by said base, and holding means cooperative with said blocks for releasably engaging such elements said blocks retaining said holding means in spaced relationship and spaced from said base.

2. A mounting for maintaining transducer elements in alignment comprising a base having channels therein, said base being adapted for supporting magnetostrictive elements, alignment blocks mounted in the channels of said base, and holding means parallel to said base cooperative with said blocks for releasably engaging such elements said blocks retaining said holding means in parallel and parallel to said base.

3. A mounting for maintaining transducer elements in alignment comprising a base having channels therein, said base being adapted for supporting magnetostrictive elements, alignment blocks mounted in the channels of said base, said blocks having slots therein, and transverse strip holders, said holders being adapted for slidable movement within said slots for releasably holding such magnetostrictive elements in alignment said blocks retaining said holders in said slots in parallel and parallel to said base.

4. A mounting for maintaining transducer elements in alignment comprising a base having channels therein, said base being adapted for supporting magnetostrictive elements, alignment blocks mounted in the channels of said base, said blocks having slots therein, transverse

strip holders being adapted for slidable movement within said slots parallel to said base for releasably holding such magnetostrictive elements in alignment at their nodal plane said blocks retaining said holders in said slots in parallel and parallel to said base.

5. A mounting for maintaining transducer elements in alignment comprising a base having channels therein, said base being adapted for supporting magnetostrictive elements, alignment blocks having slots therein parallel to said base, said blocks perpendicularly mounted in the channels of said base, transverse strip holders being adapted for slidable movement within said slots for re-

leasably holding such magnetostrictive elements in alignment, said blocks retaining said holders in said slots in parallel and parallel to said base, and caps removably mounted on said blocks for sealing said holder strips in the slots of said blocks.
